A. BERGERON

VALVE OPERATING MECHANISM

Filed March 22, 1922

Attorney

UNITED STATES PATENT OFFICE.

ALFRED BERGERON, OF WOONSOCKET, RHODE ISLAND.

VALVE-OPERATING MECHANISM.

Application filed March 22, 1922. Serial No. 545,741.

To all whom it may concern:

Be it known that I, ALFRED BERGERON, a citizen of the United States, residing at Woonsocket, in the county of Providence and State of Rhode Island, have invented 5 certain new and useful Improvements in Valve-Operating Mechanism, of which the following is a specification:—

The present invention relates more particularly to the means for taking up the necessary play or lost motion that is found necessary between the actuating rod and the valve of an internal combustion engine of the type employing a rocker arm between 15 the two. As is well known, a certain amount of lost motion is necessary in order to allow for the expansion of the valve stem, and as a consequence there is apt to be noise occasioned by the striking of the parts together.

20 The object of the present invention is to provide means which will maintain all the parts in contact, and yet allow for the necessary elongation of the same.

25 In the accompanying drawings:—

Figure 1 is a side elevation of a well known type of valve mechanism, with the improvements applied thereto.

Figure 2 is a longitudinal sectional view 30 through the lever or rocker arm mounting.

Figure 3 is a view of the fulcrum head at right angles to Figure 2,

Figure 4 is a bottom plan view of the head shown in Figure 3.

Figure 5 is a bottom plan view of the post 35 element,

Figure 6 is a side elevation of the locking nut.

In the embodiment disclosed, a valve of well known type is shown at 7, and is provided with a stem 8 surrounded by the usual closing spring 9. This stem bears 40 against one end of a rocker arm or lever 10, the other end of which is borne against by the usual valve actuating rod 11. So far as

45 thus disclosed the structure is well known in the art.

The lever 10 is fulcrumed between its ends on a mounting designated generally by the reference numeral 12. This mounting includes a base 13 having an upstanding sleeve 14 in which is adjustably threaded 50 a socket element 15 having an angular head 16, by which it may be turned. A lock nut 17, threaded on the exterior of the sleeve 14, is adapted to abut against the head 16

and prevent its accidental rotation. A post element consists of a head 19 having a journal pin 20 on which the lever 10 is fulcrumed and this head carries a depending stem 21 that is slidably mounted in the 60 socket element. It is held against turning by a screw key 22 threaded through the head 16 and engaging in any one of a number of grooves 23 formed in the lower end of the head 19. The lower end of the stem 65 21 is enlarged, as shown at 24, and is longitudinally split, as illustrated at 25, the slits tapering upwardly as illustrated. Any number of these slits may be provided, as desired. The upper surface of the enlarged 70 portion 24, is tapered, as shown at 26, and bears against the inwardly tapered surface 27 formed on the lower end of the socket element 15. The lower end of the bore in which the post is slidably mounted may be closed 75 by a plug 28 and an oil port 29 formed in the head 16 communicates with one of the grooves 23.

With this structure it is to be understood that the actuating rod 11 has at all times 80 contact with the end of the lever or rocker arm 10 and that said lever or rocker arm 10 is in constant contact with the valve stem 8. Because of these bearings there is therefore no noise in operation and if a change 85 takes place by reason of the elongation of the valve 8, for instance, the post member of the mounting will be moved upwardly. This will take place against the yielding resistance caused by the sliding bearing of the 90 surface 26 against the surface 27 and the compression of the lower end of the post element. A reverse action obviously will take place if the valve stem contracts for the resilient lower end of the post will react and expand, causing the movement 95 downwardly of the post and thus maintaining the bearing between the valve actuating parts.

From the foregoing, it is thought that the 100 construction, operation and many advantages of the herein described invention will be apparent to those skilled in the art, without further description, and it will be understood that various changes in the size, shape, proportion and minor details of construction, may be resorted to without departing from the spirit or sacrificing any of the advantages of the invention.

Having thus fully described my inven- 110

tion, what I claim as new, and desire to secure by Letters Patent, is:—

1. The combination with an actuated member and an actuating member therefor, of a motion transmitting lever interposed between the members, a post on which the lever is fulcrumed, a mounting in which the post is slidably engaged, said post having its inner end in the form of a longitudinally split yielding and compressible head, and a socket element adjustable in the mounting and surrounding the post, said socket element having its inner end bearing against the head and being slidably borne against by said head to compress the same and thereby offer yielding resistance to the sliding movement of the post.

2. The combination with an actuated member and an actuating member, of a motion-transmitting member comprising a lever fulcrumed between its ends and having said ends bearing respectively against the actuating and actuated members, and a mounting for said lever comprising a base having a socket provided with a tapered bearing surface and a post on which the lever is fulcrumed, said post having a split spring end provided with inclined surfaces bearing against the tapered surface of the socket. 30

In testimony whereof, I affix my signature.

ALFRED BERGERON.
